UNITED STATES PATENT OFFICE.

GEORGE B. PICKOP, OF NEW HAVEN, CONNECTICUT, ASSIGNOR TO MALLEABLE IRON FITTINGS COMPANY, OF BRANFORD, CONNECTICUT.

VIBRATOR.

Application filed January 2, 1926. Serial No. 78,837.

This invention relates to vibrators, and more particularly to means for attaching the vibrator or vibrator casing to a device which is to be operated upon by the vibrator, such as a flask, a casting, core box or the like used in casting operations.

It is sometimes difficult in foundry operations to remove castings from the boxes or flasks in which they are made, and very often it occurs that sand, dirt or other matter adheres to the walls of the articles and must be removed, usually by pounding on the walls of these articles, or by a scraping operation. As the boxes or flasks are quite often damaged in this manner, and as it is more or less of a tedious operation, it has been found to be much more expedient to use vibrators operated by compressed air or the like in such a manner that the vibrators are caused to act upon the flask and shake out or dislodge the material therefrom.

In such operations, it is, of course, necessary to attach the vibrator to the flask and remove it therefrom as soon as the operation is completed, so that the vibrator may be successively used upon a number of flasks. At the same time the connection between the vibrator and flask should be such that the vibrations will be transmitted to the walls of the flask without serious loss of energy or power therebetween, that is, the connection should be such that, while the vibrator may be easily and readily attached to and removed from the flask, the latter will be properly acted upon by the vibrator so that it will be shaken out in quick time. It is, therefore, quite advantageous to provide the vibrator with some sort of attaching means by which such a connection may be made.

One object of this invention is the provision of a jaw member for vibrators such that the latter may be readily attached to and detached from a flask or the like, and at the same time will bear firmly against the flask so that the vibrations will be properly transmitted thereto.

Another object of the invention is the provision of a jaw or attached member for vibrators which will fit the walls of flasks of various sizes and of various cross-sectional shapes in such a manner as to be readily attached thereto, and at the same time will properly transmit the vibrations to the flask to shake out the casting.

A still further object of my invention is the

provision of a jaw member which may be secured to or formed integrally with the vibrator head, the jaw member being of such shape that it will readily fit over the walls of flasks of various sizes and shapes to properly transmit the vibrations thereto.

A still further object of my invention is to provide an arrangement wherein the weight of the vibrator may be utilized to urge the arms of the jaw or other flask engaging element into contact with the walls of the flask.

To these and other ends the invention consists in the novel features and combinations of parts to be hereinafter described and claimed.

In the accompanying drawings:

Fig. 1 is a side elevational view of a foundry flask having attached thereto a vibrator embodying my improvements;

Fig. 2 is an enlarged side elevational view of the vibrator showing the wall of the flask in section;

Fig. 2^A is a fragmentary view of the manner in which the vibrator jaw embraces the wall of a flask of different shape;

Fig. 3 is a front view of the vibrator;

Fig. 4 is a side elevational view of a modified form of my invention showing the jaws secured to a housing within which the vibrator is adapted to be mounted.

In Fig. 1 of the drawings, I have shown in a somewhat conventional manner a foundry flask 10 supported by the chains 11 and 12 which may depend from a crane hook or the like (not shown). The side walls of the flask in this instance are channel shaped in section, and, as shown in Fig. 2, comprise a web or body portion 13 and upper and lower flanges 14 and 15.

The vibrator structure comprises a body or casing 16 provided with a compressed air inlet 17. The interior of this casing is hollow and is usually of a cylindrical shape, as shown in my prior Patent No. 1,336,921, and it is contemplated that a piston or ram be used similar to the one shown in the patent referred to.

In the particular form of my invention shown in Figs. 1 to 3 of the drawings, the opposite ends of the vibrator casing are closed by the heads 18 and 19 which may be held in position by the bolts 20 which pass through the projecting edges of the heads and securely clamp them in position upon the casing 16. A bail or the like 21 may be secured to certain of the bolts 20, the bail being provided with an eye 22 so that the vibrator itself, if desired,

may be suspended, these devices being sometimes made in very large sizes and when so made are extremely heavy. The front portion of this bail is bifurcated to provide the 5 legs 23 and 24 which span the upper part of the jaw member 25, and are secured upon the ends of certain of the bolts 20.

According to one embodiment of my invention, the jaw 25 is formed integrally with the 10 head 19 and consists of a member substantially C shaped in form having a jaw or opening of corresponding shape to receive the wall of the flask.

The jaw 25 comprises an upper substantially horizontal portion 26, a front vertically extending side 27, a rear wall 28, and a lower forwardly projecting portion 29. When in position upon the wall of a flask, the upper portion 26 will be substantially horizontally 15 disposed and will be of sufficient length to accommodate the flange 14 upon the upper wall of the flask. That is, it is contemplated that this part of the jaw be made of a length 20 equal to or greater than any flange commonly used upon the flask wall. Likewise, in order 25 that the vibrator may be readily placed upon such a flanged flask, it is desirable that the distance between the extreme end 30 of the lower C-shaped part of the jaw and the end 30 31 of the front wall 27 be at least equal to the length of the upper wall 26. When these dimensions are followed any flange will readily be received in the jaw opening which is not too long to be accommodated between the front 35 and rear members 27 and 28 of the jaw 25.

As shown in Fig. 2, when the vibrator has been placed upon the flask, it will assume a position wherein the parts of the jaw will be firmly lodged and bound against the parts of 40 the flask by the weight of the vibrator which is held in a substantially horizontal position extending outwardly from the wall of the flask, the center of gravity of the vibrator and jaw being spaced outwardly from the 45 wall, whereby considerable leverage is exerted on the arms of the jaw engaging the flask so that the vibrations will be properly transmitted to the latter member. The lower arm 29 will bear directly against the side or 50 web portion of the flask wall and the flange 14 will assume a position across the angle between the sides 26 and 27 of the jaw.

Likewise, as shown in Fig. 2, the same jaw will readily be accommodated to the walls of 55 flasks which have a flange of any width less than the length of the part 26 or to flask walls which are provided with no flange at all. This is particularly shown in Fig. 2^A of the drawings where the vibrator is shown positioned upon a flask, the wall of which has a 60 very short flange. It will be seen that the vibrator is in substantially the same position in Fig. 2^A as in Fig. 2, and for this reason a vibrator provided with a jaw member of this 65 type has universal application to the side

walls of foundry flasks or kindred devices without regard to the exact cross-sectional shape of these walls, so long as the wall of the flask may be received between the points 30 and 31.

In Fig. 4 of the drawings, I have shown a vibrator casing 35, having heads 36 and 37 secured thereto, these heads being provided with projecting lugs 38 and 39. The vibrator casing 35 is mounted within a housing 40 having a body portion 41, side shoulders 42 and 43, and legs 44 and 45 designed to lie against the lugs 38 and 39 and be secured thereto. The side shoulders 42 and 43 are adapted to closely embrace the heads 36 and 37 of the vibrator housing so that a firm contact is made therebetween. A jaw member 46 is secured in this instance to the housing 40, this jaw member preferably being of the same shape as the member 25 described in connection with Figs. 1 to 3 of the drawings. It will be apparent, therefore, that this jaw member may either be directly formed upon or secured to one of the vibrator heads, or may be secured to the housing within which the vibrator is adapted to be mounted. When, as shown in Fig. 4, the jaw member is provided upon the housing, it will be apparent that, as the vibrator may be readily attached to and detached from the housing, the former 90 may be used if desired with a number of housings having differently shaped jaw members which may be adapted for different classes of work. These housings may be provided with bails 47 to assist in the handling 100 of the device.

While I have described and shown some preferred embodiments of my invention, it will be understood that it is not to be limited to all the details shown, but is capable of 105 modification and variation within the spirit of the invention and within the scope of the appended claims.

What I claim is:

1. A vibrator comprising a casing and a 110 jaw member rigidly secured thereto, said jaw member being provided with an opening adapted to receive a part of a member to be vibrated and to support the vibrator thereon.

2. A vibrator comprising a casing and an 115 open mouthed jaw member rigidly secured thereto, said jaw member being adapted to receive and embrace a part of a member to be vibrated and to support the vibrator thereon in a substantially horizontal position.

3. A vibrator comprising a casing having an open mouthed jaw member secured thereto, 120 said jaw member having substantially parallel front and rear walls designed to embrace a part of a member to be vibrated, and an upper wall designed to rest against such part.

4. A vibrator comprising a casing having an open mouthed jaw member rigidly secured thereto, said jaw member having front and rear portions between which a part of the 125

- member to be vibrated is adapted to be received, and an upper wall designed to rest upon such part.
5. A vibrator comprising a casing having an open mouthed jaw member rigidly secured thereto, said jaw member having front and rear portions between which a part of the member to be vibrated is adapted to be received, and an upper wall and lower arm designed to rest against such part.
6. A vibrator comprising a casing having secured thereto an open jaw member of substantially C-shaped form, the opening in such member being not less than the length of the upper wall thereof.
7. A vibrator casing having secured thereto an open mouthed jaw member comprising an upper wall with front and rear depending sides, the opening of said jaw member being not less than the length of the upper wall.
8. A vibrator casing having secured thereto an open mouthed jaw member comprising an upper wall with front and rear parallel depending sides, the opening of said jaw member being not less than the length of the upper wall.
9. A vibrator comprising a casing having an open mouthed jaw member secured thereto, and designed to receive therewithin the side wall of a foundry flask or the like, said jaw member having an upper wall designed to rest against the top portion of the side wall of the flask, and a depending leg disposed at substantially right angles to said wall adapted to be positioned within the flask adjacent the inner surface of the side wall thereof.
10. A jaw member for vibrators having an upper wall and front and rear depending sides, and a member on one of said sides and projecting toward but terminating short of the other side, and means for securing said jaw member to a vibrator casing.
11. A jaw member for vibrators or the like having an upper wall and front and rear depending sides, one of which is longer than the other, and a member at the lower end of the longer side projecting toward but not to the other side so as to provide a large opening between the shorter side and the projecting member, and means for securing said jaw member to a vibrator casing.
12. A jaw member for vibrators or the like, having an upper wall designed to rest at the upper portion of a member to be vibrated, and spaced depending portions designed to lie on opposite sides of such member.
13. A jaw member for vibrators or the like, having an upper wall designed to rest on the upper portion of a member to be vibrated, spaced depending portions designed to lie on opposite sides of such member, and a forwardly projecting member at the lower end of one of said spaced projecting portions designed to abut the member to be vibrated.
14. A jaw member for vibrators or the like, having a depending portion designed to hook over a member to be vibrated, and a forwardly projecting portion designed to abut against a side of such member.
15. A jaw member for vibrators or the like, having upper and rear sides, and lower and front sides of shorter length respectively than the upper and rear sides, thereby leaving an opening between the front and lower sides for the reception of the member to be vibrated, and means for securing said jaw member to a vibrator.
16. A jaw member for vibrators or the like, generally of quadrangular form, said member having an opening at one corner thereof for the reception of a part of the member to be vibrated.
17. A jaw member for vibrators or the like, said member being generally of quadrangular form and having two of its adjacent sides of shorter length than the opposite sides respectively, whereby an opening is left between the two shortened sides for the reception of a part of a member to be vibrated.
18. In a vibrator, a casing, a ram mounted in the casing for vibratory movement, and means attached to the casing for embracing a part to be vibrated and supporting said casing spaced outwardly from said part, whereby said means may be urged into contact with said part by the weight of said vibrator.
19. In a vibrator, a casing, a ram mounted in the casing for vibratory movement, and means attached to the casing for embracing a part to be vibrated and supporting the vibrator thereon in a substantially horizontal position, said embracing means being adapted to be urged into contact with the part by the weight of the vibrator.
20. In a vibrator, a casing, a ram mounted in the casing for vibratory movement, and means attached to the casing for engaging a part to be vibrated and supporting said vibrator, comprising means for engaging an inner surface of said part, and means for engaging an outer surface of said part, both of said means being adapted to be urged into contact with the part by the weight of said vibrator.
21. In a vibrator, a casing, a ram mounted in said casing for vibratory movement, means for transmitting vibrations to a part to be vibrated, comprising means for pivotally supporting the vibrator on the part, and means for engaging a wall of said part to limit the movement of the vibrator about its pivotal support, said wall engaging means being adapted to be urged into contact with said wall by the weight of the vibrator.
22. In a vibrator, a casing, a ram mounted in said casing for vibratory movement, and means for supporting said vibrator in a substantially horizontal position on and in alignment with the part to be vibrated, said

means comprising an arm adapted to engage an inner wall of the part, an arm adapted to engage an outer wall of the part, and means adapted to rest on an upper surface of the part, said last named means being spaced outwardly from the extended path of said ram at least as far as the upper edge of said casing.

23. In a vibrator, a casing, a ram mounted in the casing for vibratory movement, and means attached to the casing for embracing

a part to be vibrated and supporting the vibrator thereon, said vibrator when so supported extending outwardly from the part in a position inclined slightly below the horizontal, whereby said embracing means may be urged into contact with the part by the weight of the vibrator. 15

In witness whereof, I have hereunto set my hand this 30th day of December, 1925.

GEORGE B. PICKOP.
